EXTINGUISHER

Adolph H. Smeby, Los Angeles, Calif., assignor to
Jay B. Hinson, Hartsdale, N. Y.

Application August 29, 1939, Serial No. 292,372

2 Claims. (Cl. 131—237)

This invention relates to extinguishers and is herein disclosed in some detail as a cigarette extinguisher in an attractive form, as including an ash tray, and as adapted to be made of stamped parts and sold at a very low price.

The menace of the lighted stubs of discarded cigarettes has been increasing for years, and many types of receivers have been devised for use in clubs, homes, hotels and elsewhere, but many of these receivers are simply metal or porcelain saucers, often ornamental, for retaining the glowing stubs until they burn out and then retaining all the burned stumps.

Such receivers are not always at hand, and even if they are the glowing cigarettes they retain are often offensive and always a menace. In a travelling automobile a mere receiver is a menace, and, moreover, is not always convenient, with the result that sixty percent of the forest fires are said to have been started by the stubs of unextinguished cigarettes.

According to the present invention the foregoing and other difficulties, objections and dangers are overcome, by providing a positive extinguisher for the cigarette, and yet a device whose use is obvious, natural and convenient.

In the form shown, the end of the glowing cigarette stub is inserted in a sleeve by pushing it with the fingers, and the sleeve yields, so that the fingers naturally push the cigarette guided by the sleeve against a projecting point as of a conoidal member with the result that the cigarette end is pinched against the wall of the sleeve extinguishing the sparks.

When the finger is withdrawn the sleeve springs back, and the cigarette end is withdrawn, any ashes falling into a cup or other receiver.

Other features and advantages will hereinafter appear.

In the accompanying drawing:

Figure 1 is a top view of one form of the invention.

Figure 2 is a sectional view on line 2—2 of Figure 1.

Figure 3 is a similar view showing a cigarette being extinguished.

The extinguisher shown includes a base 10, on which a light U-shaped resilient strap 11 is shown as centrally mounted by one end 12. The opposite free end 13 of the strap 11 is shown as carrying a vertically mounted metal sleeve 14 a little larger than a standard cigarette and a fraction of an inch long.

To extinguish a cigarette, the cigarette is held in the usual manner by the fingers and its glowing end pushed downward into the sleeve until the fingers strike the annular horizontally projecting upper edge 15 of the sleeve.

Then the cigarette and sleeve move downward-

ly together until the glowing end of the cigarette encounters a blunt upper point 16 as of a conoidal member 17. Further downward movement of the fingers pinches the cigarette outwards against the sleeve wall, cutting off the oxygen needed for combustion, and holding it so that the fingers crush the body of the cigarette down upon it. In addition, the member 17 may be solid metal, thus chilling any glowing sparks and completing the extinguishing.

In the form shown, the member 17 carries at its base a threaded extension 18 which passes through the base 10 and is shown as drawn down by a nut 19, thus firmly holding both the member 17 and the end 12 of the strap 11, because the strap is shown as held by the member 17 against the base 10.

The base 10 is shown as having a boss 20 at the center, so that ashes within it tend to fall 20 away from the member 17, and also holding the nut 19 clear of any table the base may rest upon. The outer edge of the base is turned up at 21 so the base forms a closed cup for holding the extinguished stubs and ashes, and may also form 25 a rest for lighted cigarettes.

In many cases the cigarette does not slip through the collar or sleeve 14 but catches it when it is inserted and carries the collar down so that the glowing end of the cigarette almost 30 immediately strikes the point 16 of the member 17, and forces the body of the cigarette outward, pinching it between the member 17 and the collar 14.

In Figure 3 the cigarette is shown held approximately a full half inch back of the burning edge of the wrapper, most of the ashes having fallen off as shown.

Having thus described certain embodiments of the invention, what is claimed is:

40. 1. A cigarette extinguisher including a sleeve a little larger than a cigarette, a pointed member facing the open end of the sleeve and expanding to a base of a size to pinch the cigarette between the base and the sleeve and thereby extinguish it, a fixed mount for the pointed member, and a mounting for the sleeve on which it is adapted to move with the cigarette to effect the extinguishing of the cigarette.

2. A cigarette extinguisher including a sleeve a little larger than a cigarette, a conoidal member facing the open end of the sleeve and expanding to a base of a size to pinch the cigarette between the base and the sleeve and thereby extinguish it, a fixed mount for the pointed member, and a resilient mounting for the sleeve so that it is adapted to move with the cigarette to effect the extinguishing of the cigarette.

ADOLPH H. SMEBY,
